UNITED STATES PATENT OFFICE.

MARTHA A. BAILEY, OF LIMA, OHIO.

PACKAGE-TIE.

961,833.

Specification of Letters Patent. Patented June 21, 1910.

Application filed February 2, 1910. Serial No. 541,562.

To all whom it may concern:

Be it known that I, MARTHA A. BAILEY, a citizen of the United States, residing at Lima, in the county of Allen and State of Ohio, have invented certain new and useful Improvements in Package-Ties, of which the following is a specification.

This invention relates to new and useful improvements in package ties and is adaptable to bundles of various sizes, being designed to provide a device of this character which will not only be substantial and adjustable in its construction but will have a means provided thereon for securely locking the same about the bundle.

With the above and other objects in view, this invention consists of the construction, combination and arrangement of parts all as hereinafter more fully described, claimed and illustrated in the accompanying drawings, wherein:

Figure 1 is a perspective view of a package tie constructed in accordance with the present invention; Fig. 2 is a central longitudinal section of the sheath thereof; Fig. 3 is a transverse section of Fig. 2.

The package tie forming the subject-matter of the present invention comprises a sheath A, said sheath being approximately elliptical in cross section, the base thereof being substantially flat. The upper side of the sheath is provided with a slot 10, said slot extending the entire length of the sheath. At the rear extremity of the sheath is provided an outwardly projecting lug or ear 11, formed integrally with the base thereof and provided with a transverse slot 12. The slot 12 provides a means whereby the strap 13 forming the main body portion of the tie is secured to the sheath, the same being passed through the slot, bent upon itself and secured in this position. The extremities of the sheath are rounded to present a smooth and finished edge in order that no damage may be imparted to the bundle secured thereby.

A series of transverse bars 14 are attached to the base of the sheath and are convexed therefrom forming a space whereby the

hook carried by the opposite extremity of 50 the strap 13 may engage said sheath.

The hook indicated in general as B comprises a main hook member 15, the outer extremity 16 of which is constructed somewhat similar to a safety pin. A catch 17 is oppositely disposed with respect to said hook and is adapted to engage the hook portion 16 thereof. The catch and hook are connected at their lower extremities by an approximately rectangular spring portion 18 to 60 which is secured the strap by passing the catch portion through the strap at any predetermined interval and allowing the former to bear against the straight portion 18.

From the foregoing it will readily be seen 65 that the hook may be placed at any desired point on the strap, thus supplying a means of adjusting the same to bundles of various volumes. A further adjustment is obtained in the sheath A, the hook portion 15 being 70 passed under the cross bars 14 until the desired point is reached, the hook 16 then being projected upwardly and engaged by the catch 17, said catch resting on the exterior of said cross bars. Two adjustments 75 of the tie are thus had, making the present invention applicable to substantially all sizes of bundles.

Having thus described my invention, what is claimed as new is:

An article of manufacture comprising in combination, a sheath approximately elliptical in cross section provided with a longitudinally extending slot in the upper side, and a rearwardly projecting slotted ear on 85 the base thereof, a series of convexed bars secured to said base, a strap secured in said slotted ear, and a hook carried at the opposite extremity of said strap and adapted to be attached at various positions on said strap 90 and also adapted to engage one of said convexed bars.

In testimony whereof I affix my signature in presence of two witnesses.

MARTHA A. BAILEY.
